UNITED STATES PATENT OFFICE.

JOHN L. PLANK, OF ROCHESTER, NEW YORK.

DEPOSIT AND COLLECTION RECEPTACLE.

1,260,038.

Specification of Letters Patent. Patented Mar. 19, 1918.

Application filed January 31, 1916. Serial No. 75,291.

To all whom it may concern:

Be it known that I, JOHN L. PLANK, a citizen of the United States, and resident of Rochester, in the county of Monroe and State of New York, have invented certain new and useful Improvements in Deposit and Collection Receptacles, of which the following is a specification.

The present invention relates to mail receiving and collecting receptacles and an object thereof is to provide a construction in which there is no liability of the collector failing to gather all of the mail within the receptacle. Another object of the invention is to provide a construction which will permit the entire contents of the receptacle to be deposited within a mail bag or pouch without requiring any handling of the mail by the collector, and without exposing the mail to the elements. A further object of the invention is to provide a construction which, while permitting the discharge of the contents through the bottom of the receptacle will enable the bottom to assume another open position where it will act to retain the mail for the hand-collecting. Another object of the invention is to provide a device which will co-operate with the closure of a mail box, for the purpose of providing a pocket on said closure to receive the mail from the box. A still further object is to provide for rendering this pocket-forming member inoperative when a bag or pouch is attached to the box. Still another object of the invention is to prevent the removal of the key of the box until the closure of the box has been moved to closed position and locked in such position. A still further object of the invention is to prevent the removal of the bag or pouch until the closure is locked in closed position.

To these and other ends, the invention consists in certain parts and combinations of parts all of which will be hereinafter described, the novel features being pointed out in the appended claims.

In the drawings:—

Figure 1 is a vertical section through the box or receptacle showing the bottom closed;

Figs. 2 and 3 are views similar to Fig. 1, showing the bottom, respectively, in extreme open position and in intermediate open po-

sition, where it receives the mail from the receptacle;

Fig. 4 is a section on the line *a—a* of Fig. 1;

Fig. 5 is a section on the line *b—b* of Fig. 1;

Fig. 6 is an inside view of the lock;

Fig. 7 is a sectional view of the lock; and

Fig. 8 is a detail view, showing the manner of holding the key against removal while the lock is in unlocking position.

Referring more particularly to the drawings, 1 indicates a box or any receptacle having the usual mail receiving slot (not shown), and having a discharge opening preferably arranged at the bottom thereof. This discharge opening is closed by a cover 70 or closure 2, which, preferably, is hinged at 3 to the rear wall of the receptacle, and when in closed position projects forwardly beyond the front wall.

Arranged about the lower portion of the box or receptacle is a hood 4 which, preferably, is spaced from the front and the side walls to provide a chamber 5, the hood projecting downwardly below the lower end of its rear wall through which extend supporting projections 7, which are secured to the closure 2, and extend rearwardly therefrom, being preferably formed with recesses or depressions 8, for the purpose of supporting 85 a bag or pouch 9, as will be hereinafter set forth.

Under normal conditions the cover 2 will drop downwardly to the position shown in Fig. 2, in order to discharge the entire contents of the mail box or receptacle into a bag or pouch 9. This bag or pouch has a mouth of such a size that it will fit snugly about the hood 4, and in order to support it upon the hood said bag is provided with two openings 10 near its mouth for fitting over the projections 7, while the closure is in closed position. Also provided on the bag or pouch 9, near the mouth thereof, are two pins or projections 11 adapted to be inserted through openings 11^a in the front wall of the hood 4.

The box is also capable of being used without the bag or pouch, and when so used the cover or closure 2 does not swing to its 105 extreme open position, but instead is em-

ployed for holding the mail until it is removed by the collector. To the end that the mail will be retained upon the cover or closure, there may be provided a mail-retaining member, which, preferably, is in the form of a U-shaped frame 12, in this instance pivoted at 13 to the side-walls of the box 1 and within the hood 4, so that said frame is adapted to surround the lower end 5 of the box and to rest upon the cover 2. In order that this mail-retaining wall or frame 12 may be held from swinging downwardly with the cover 2, when the bag or pouch is fitted to the box, said retaining-frame or member has its front wall provided with two openings which are adapted to align with the openings 11^a in the front wall of the hood 4, so that when the projections 11 are passed through the openings of the front wall they will also pass through the openings in the retaining-frame or member (as shown in Fig. 1), and hold said retaining-frame against movement, but if the retaining-frame is not so held, it will drop by 10 gravity with the cover 2 and form a pocket 20 for holding the mail on the cover 2, as shown in Fig. 3.

With the object in view of locking the retaining-member to the cover or closure, when both of these parts swing downwardly together, an interlocking connection is provided between said parts. This connection is preferably in the form of hooks or projections 15 depending from the underside 30 of the frame or member 12, and operating in slots or openings 16 in the cover or closure 2. When the retaining-member or frame 12 is held against downward movement, this interlocking connection is ineffective, but owing to the fact that the centers of turning of the cover 2 and the retaining-member 12 are different, there is a slight sliding action of the retaining-member on the cover-member, and this sliding action causes the hooks or projections 15 to move in the slots 16 and to interlock with the closure 2, eventually causing both the closure and the retaining-member 12 to stop at an inclined position, as shown in Fig. 3, 35 where said cover will receive the contents of the box or receptacle.

Any suitable locking means for the cover or closure may be employed, but in the preferred construction the lock is held against operation so long as the cover or closure is not in closed position. In the illustrated embodiment the locking-device or mechanism embodies a bolt 17, slidably mounted on the inner face of the front wall of the hood and carrying a projection 18, which is adapted to pass through a recess 19 in the cover-member, in order to engage beneath the cover-member to support the latter in closed position. This bolt is controlled by a key-barrel 20 which has a pro-

jection 21 engaging the bolt to shift the latter in opposite directions. The bolt is locked against movement by one or more tumblers 22 pivoted at 23 and lying in the path of a projection 24 on the bolt when the latter is in locking position. This tumbler also has a recess 25 into which the projection 24 enters when the tumbler has been moved to free the bolt, and one wall 26 of this recess serves as a shoulder for engaging the projection 24 after the bolt has been moved to unlocking position. The tumbler is controlled by the key 31 and is elevated both upon the locking and unlocking movement of the key-barrel prior to 75 the shifting of the bolt. The key-barrel may be provided with a surrounding groove 28 in which is received an annular flange 29 on the escutcheon plate, the flange being formed with a notch 30 through which 80 the key 31 may be introduced into the key-barrel, the key 31 having a notch 32 which receives the flange 29, when said key is turned to unlock the locking-mechanism, thus preventing the removal of the key except when the locking-mechanism is shifted to locking position.

To the end that the locking-mechanism shall not be moved to locking position except when the closure or cover 2 is in closed 95 position, there is provided a detent 33 in the form of a slide movable into the path of the projection 18 of the locking-bolt to prevent the movement of the latter to locking position. This slide or detent has a 100 projection 34 extending into the hood in the path of the cover or closure 2, so that when the closure is moved to closed position, it elevates the detent 33 from the path of the locking-bolt 17 and vice versa, thus 105 preventing the removal of the key 31 until the cover or closure 2 is moved to closed position. It is preferred to position the locking barrel at a point below the upper edge of the mail-bag or sack when the latter is attached to the box, and to provide the mail-bag or sack with an opening 35 which registers with the key-opening, so that the key will project through the bag or sack and lock the latter to the mail-box. 110 With this arrangement the bag cannot be removed until the key is removed, and the key cannot be removed until the closure 2 is moved to closed position and secured by the locking-mechanism.

A mail-receiving box or receptacle constructed in accordance with this invention may be employed for discharging its contents into a bag or sack while the latter is attached to the box, or the mail may be collected by hand from the box in the manner that has been customary. When the box is used to discharge its contents into a bag or pouch, the entire bottom of the receptacle swings open to a vertical position, so 115 120 125 130

there are no ledges on which mail matter may collect. The bag or pouch entirely surrounds the lower end of the mail-receiving receptacle and is supported in an open

5 position thereon, being held to the box to prevent removal until the box has been closed, thus doing away with the necessity of the handling of the mail by the collector and preventing wind or rain reaching the
10 mail in its discharge from the box to the bag or pouch. If the bag is not to be used, the closure does not move to the extreme open position but is stopped at an intermediate point, and the mail-retaining member is brought into coöperation with the closure to form a pocket into which the
15 mail matter is discharged, and from which it is removed by the collector. In both instances the key of the locking-mechanism cannot be removed until the closure is moved to closed position and locked in such position, thus preventing the collector from leaving the box unlocked.

What I claim as my invention and desire
25 to secure by Letters Patent is:

1. In combination in a mail-receiving receptacle having a discharge-opening, a closure for said discharge-opening, and a mail-retaining member for forming a pocket
30 on said closure, mounted to move with said closure and also to remain stationary while the closure moves relatively thereto.

2. In combination in a mail-receiving receptacle having a discharge-opening, a pivoted closure for said discharge-opening, and a pivoted mail-retaining member for forming a pocket on said closure, the closure being movable relatively to the mail-retaining member.

40 3. In combination in a mail-receiving receptacle having a discharge-opening, a pivoted closure for said discharge-opening, and a U-shaped member having its arms pivoted to the mail-receiving receptacle so that the closure may move relatively thereto, said member being constructed to coöperate with the closure in order to form a pocket for receiving mail matter from the receptacle.

50 4. In combination in a mail-receiving receptacle having a discharge-opening, a pivoted closure for said opening, a mail-receiving member pivoted to turn about a center different from that about which the closure turns and to coöperate with the closure to form a pocket for receiving mail from the receptacle, and devices for interlocking the mail-receiving member with the closure when said member is not held against movement and the closure is moved to open position.

55 5. In combination in a mail-receiving receptacle having a discharge opening, a pivoted closure for said opening, an independently pivoted mail-receiving member,

and a hook carried by one of the last-named two parts to engage the other part when the mail-receiving member is not held against movement and the cover is moved to open position.

6. In a mail-receiving receptacle having a discharge-opening in its bottom, a closure for said opening movable to two open positions, one to receive the mail from the receptacle and the other to permit the entire
70 discharge of the contents, and a mail-receiving member lying in coöperation with said closure when the closure assumes the first-named position and out of coöperation with the closure when the latter assumes
75 the second-named position.

7. In a mail-receiving receptacle, the combination with a main box-portion having its bottom open, a closure for said bottom of the box-portion, a hood spaced from the front and side walls of said box-portion and having the forward end of the closure projecting therein, a U-shaped frame partially surrounding the box-portion within the hood and having its arms pivoted in proximity to the rear wall of the box-portion, said frame being adapted to coöperate with the closure to form a mail-receiving
80 pocket.

8. In a mail-receiving receptacle, the combination with a box-portion having a discharge-opening at its bottom, a swinging closure for said discharge-opening, a swinging mail-receiving member for coöperating with said closure, and a pouch for receiving the mail from the box-portion, having means for engaging the mail-receiving member to hold the latter in inoperative position.

9. In a mail-receptacle having a discharge-opening in its bottom, a closure for said discharge-opening, a member for coöperating with said closure to provide a pocket for receiving the mail, and a mail-bag for attachment to the receptacle, having means for holding the mail-receiving member out of coöperation with the closure.

10. In a mail-receptacle, the combination with a box-portion having its bottom open, a hood spaced from the front and side-walls of said box-portion, a closure pivoted at its rear to close the bottom of the box-portion and projecting at its sides and forward edge into the hood, a U-shaped frame having its arms pivoted near the rear walls of the box-portion, said frame surrounding the lower portion of the box-portion within the hood to provide a pocket on the closure, and a bag for receiving the mail from the box-portion having projections for interlocking with said frame to hold the latter out of coöperation with the closure.

11. In a mailing-receptacle having a discharge-opening at its bottom, a closure for said discharge-opening, a key-controlled

locking-mechanism for said closure, a bag adapted to be attached to said receptacle above said locking-mechanism, and provided with an opening through which a key may be passed to control the locking-mechanism.

12. In combination in a mail-receiving receptacle having a discharge-opening, a closure for said opening, a key controlled lock for the closure, a bag adapted to be at-

tached to said receptacle above said key controlled lock and provided with an opening through which the key must be passed to control the lock, and means preventing the removal of the key from the lock when the closure is open, said means being controlled by said closure. 15

JNO. L. PLANK.
